Elmer Eaves,
INVENTOR

BY *Victor J. Evans & Co.*

ATTORNEY

WITNESS:

UNITED STATES PATENT OFFICE

ELMER EAVES, OF BATESVILLE, MISSISSIPPI

BARBER MUG

Application filed February 26, 1932. Serial No. 595,383.

My present invention relates to shaving cups or mugs and my primary object is the provision of an article of this character which may be conveniently and readily cleaned and, 5 therefore, retained in a sanitary condition.

To the attainment of the foregoing the invention consists in the improvement herein-after described and definitely claimed.

In the drawing:

10 Figure 1 is an approximately central vertical longitudinal sectional view through a shaving mug in accordance with this invention.

15 Figure 2 is a similar view but showing the valve plate in open position to permit of the saponaceous fluid in the cup being drained through the apertured bottom thereof as when water from a faucet is directed through the mug.

20 Figure 3 is a plan view of the valve.

Figure 4 is an inverted plan view of the mug with the valve removed.

25 The shaving mug 1 is of the usual construction, the same being provided on one of its sides with a handle that defines an upper straight portion 2 and an angle portion 3 which is connected adjacent to the bottom of the mug. The mug has arranged therein a pedestal that affords a rest for a cake of 30 soap 4, and the bottom of the mug is provided with the usual outstanding rim 5 whose inner wall, in the present instance, is straight, while the bottom 6 of the mug is provided with a series of apertures or openings 7.

35 Arranged in the rim, in contact with the peripheral wall afforded thereby, and likewise in contact with the outer face of the bottom 6 there is a disc valve 8. The valve 8 is of any desired material that will afford a tight 40 closure for the openings 7, and the valve is formed with an outwardly directed flat lug 9 which is pivoted, as at 10, between the side walls afforded by a notch 11 in the rim 5.

45 The notch 11 is disposed directly below the angle portion 3 of the handle, and the outer end of the lug 9 is centrally slotted and has its sides provided with elongated openings 12 for the reception of a pin 13 that passes through the rounded end 14 of a rod 15. The 50 head of the rod is received in the slotted por-

tion of the lug 9, and the angle portion 3 of the handle is provided with a bore 16 that enters from its lower end and with a reduced opening 17 that communicates with the bore 16 and with the upper portion 2 of the handle. 55 The rod 15 extends through the bore 16 and through the opening 17. The rod 15 has fixed thereon a stop element 18 that is engaged by one end of a coil compression spring 19 that is received in the bore 16 and that has its second end contacting with the shoulder provided between the bore and the opening 17.

60 The outer portion 2 of the handle, from the outer wall afforded by the opening 17, has its upper face notched or slotted, as at 20, and pivoted, as at 21, in this slot there is an angle lever 22. The lower or horizontal arm of the angle lever is formed with a somewhat elongated longitudinally arranged slot 65 or opening 23, and the upper or projecting end of the rod 15 has a bifurcated head portion 24 through which is passed a pin 25 that is received in the slot 23 of the lever 22. 70

75 The spring normally influences the rod to force the valve 8 against the apertured bottom of the cup to close such apertures. The particular and peculiar arrangement of the handle permits of the fingers and palm of the tonsorial artist or operator gripping the part 3 of the said handle and permitting his thumb to rest on the horizontal portion of the angle valve operating handle 22 which assists the spring in holding the valve closed.

80 After the shaving operation the lather which remains in the mug may be readily removed therefrom by arranging the mug beneath a faucet and by the operator swinging the angle lever by the contact of the thumb with the normally vertical arm of the said lever to swing the lever to cause the same to draw upon the rod to compress the spring and thus open the valve. The valve is only opened to a determined angle so that the saponaceous 85 fluid forced by the water through the apertures 7 cannot splash against the clothes of the operator, but will be positively directed into the basin with which the faucet is associated.

Having described the invention, I claim:

A shaving mug having a handle defining an upper straight portion and an outer angle portion which is provided with a bore that enters from its lower end and an upper opening that communicates with the bore, said mug having its lower portion provided with an annular rim and its bottom apertured, a flap valve received in the rim for normally contacting the bottom of the mug to close the apertures therein and said valve having a lug extension which is pivoted to the rim and which has its outer portion slotted longitudinally and transversely and which projects beyond the rim, a rod having its ends headed and apertured received through the bore and the opening in the outer end of the handle and the lower head being received in the longitudinal notch of the lug on the valve, a pin passing through said head and through the transverse alining openings in the lug, a stop element on the rod, a coiled expansion spring in the bore of the handle contacting with the upper wall of said bore and with the stop element, and an angle lever pivotally secured in the upper element of the handle and having its lower and horizontal arm slotted and said slot receiving therethrough a pin on the upper head of the rod.

In testimony whereof I affix my signature.
ELMER EAVES.
